UNITED STATES PATENT OFFICE.

PETER BURT, OF HOLLYBANK, BOTHWELL, SCOTLAND.

INTERNAL-COMBUSTION ENGINE.

SPECIFICATION forming part of Letters Patent No. 696,547, dated April 1, 1902.

Application filed August 19, 1901. Serial No. 72,525. (No model.)

To all whom it may concern:

Be it known that I, PETER BURT, a citizen of the United Kingdom of Great Britain and Ireland, residing at Hollybank, Bothwell, 5 Scotland, have invented certain new and useful Improvements in and Relating to Internal-Combustion Engines, (for which application for patent has been made in Great Britain, No. 23,696, dated December 28, 1901,) of 10 which the following is a specification.

This invention has reference to internal-combustion engines of the class having their cylinders arranged in tandem fashion and having single-acting pistons working in the 15 Beau de Rochas or ordinary four-step cycle and transmitting their impulses both in the same direction.

My improvements consist (as shall be hereinafter described in such a manner as to be 20 readily understood by those having a knowledge of the art to which it relates) in constructing engines of this class so that advantage may be taken of the principle of "compounding" for the purpose of expanding the 25 charges beyond their original volume, as well as to provide means whereby a current of cool air may be sent through the compression-space of each cylinder at the end of its exhaust-stroke for the purpose of displacing the 30 products of combustion from and cooling said compression-space.

In the drawings, Figure 1 is a vertical section through the cylinders. Fig. 2 is a cross-section taken on the line $x-x$ in Fig. 1.

35 These drawings illustrate an internal-combustion engine constructed in accordance with my invention. The engine therein illustrated is a vertical "tandem engine," having all its cylinder above, and its pistons acting upon 40 one crank, each of the high-pressure pistons receiving an impulse each cycle.

As shown by the drawings, in carrying out 45 my invention I place between the high-pressure cylinders a and b and in the same line therewith a proportionately larger cylinder c , hereinafter termed the "low-pressure cylinder," the respective pistons d , e , and f of these cylinders being connected together by a piston-rod g and the lower piston e acting by 50 means of its connecting-rod h upon the engine-crank. The exhaust-ports i, j of the high-pressure cylinders a and b , respectively, are

connected together (outside of the exhaust-valves i' , which are balanced) by means of a pipe k , the port j being connected with the 55 bottom end of the low-pressure cylinder by means of a passage l . At the end of each impulse-stroke in the high-pressure cylinders these cylinders exhaust alternately into the low-pressure cylinder, which latter being 60 larger in area (as its piston moves to the end of its upward stroke) expands the hot gases to a still greater volume, the piston finally uncovering a series of exhaust-ports m in the cylinder c , whence these gases are free 65 to make their escape to the atmosphere. The air-inlet ports n and o of the high-pressure cylinder a and b , respectively, and the upper end of the low-pressure cylinder c are connected together (outside the air-valves n' of 70 the former) by means of a pipe p , this pipe being fitted with an automatic non-return valve q . The low-pressure piston f on its downstroke draws in a charge of air by way of the valve q , which charge of air being 75 pressed on the return stroke of the piston f rushes (when either of the air-valves s of the high-pressure cylinders a b are opened) through the compression-space and escapes 80 by the ports in the low-pressure cylinder c , 80 sweeping before it the products of combustion and at the same time cooling those chambers and valves.

If desired, air can be admitted behind the 85 valve n' through a valve q' , as shown in Fig. 2, said valve q' having the same function as the valve q , (shown in Fig. 1;) but it is not necessary to have any valve, such as valve q' , behind the valve n' .

The piston-rods and pistons are made hollow, so that these may be kept cool by means of air or water, the air or water being admitted by a pipe r from any air or water supply. The pipe r extends downward through the hollow piston-rods s and g to near the closed 95 bottom of the latter and is provided with an open lower end, from which the water or air passes and enters the hollow piston e by orifices in the piston-rod, the water or air circulating upward by way of the annular space 100 between the pipe r and the piston-rod g to the interior of the piston f and d , whence it finally escapes by way of the annular space in the piston-rod s .

What I claim is—

1. In an internal-combustion engine, the combination, with a low-pressure cylinder, of two high-pressure cylinders of smaller diameter than the low-pressure cylinder and arranged axially in line with it and at opposite ends thereof, an exhaust-pipe connecting the working ends of the high-pressure cylinders, and a passage connecting the said exhaust-pipe with the working end of the said low-pressure cylinder, substantially as set forth.

2. In an internal-combustion engine, the combination, with a low-pressure cylinder, of two high-pressure cylinders of smaller diameter than the low-pressure cylinder and arranged axially in line with it and at opposite

ends thereof, an exhaust-pipe connecting the working ends of the high-pressure cylinders, a passage connecting the said exhaust-pipe with the working end of the said low-pressure cylinder, an air-pipe connected with the working ends of the said high-pressure cylinders, and a passage connecting the said air-pipe with the opposite end of the said low-pressure cylinder, substantially as set forth. 25

In witness whereof I have hereunto set my hand in presence of two witnesses.

PETER BURT.

Witnesses:
